UNITED STATES PATENT OFFICE.

JOHN T. DICKEY, OF TRENTON, NEW JERSEY.

PAD-COVER FOR CARRIAGE-STEPS.

SPECIFICATION forming part of Letters Patent No. 349,986, dated September 28, 1886.

Application filed March 17, 1886. Serial No. 195,574. (No model.)

To all whom it may concern:

Be it known that I, JOHN T. DICKEY, of Trenton, in the county of Mercer and State of New Jersey, have invented new and useful 5 Improvements in Rubber-Pad Covers for Carriage-Steps; and I do hereby declare that the following is a full and accurate description of the same.

Rubber-pad covers for carriage steps have been employed heretofore; but they have always been secured in place by clamps of some kind secured by screws to the metallic step. Usually they have a thin margin adapted to fold over the edge of the step and be clamped 15 against the under side thereof by a frame secured with screws.

The object of my improvement is to avoid the necessity of using screws or clamps of any kind, and therefore to avoid the liability of 20 loosing detachable parts and the difficulties attending the placing and securing the pad in that or any similar way, by making the pad with a pocket on its under side having sufficient elasticity to permit it to be passed over 25 the corners of the shoe, and yet rigidity enough to retain its shape and place after being so attached.

In the accompanying drawings, Figure 1 is a perspective view of my pad in position. 30 Fig. 2 is a perspective view of the same from the under side. Fig. 3 is a transverse section of the same.

A is the carriage-step, of ordinary construc-

tion, being composed of a flat plate of metal, with a leg, *g*, extending up to and usually attached to the carriage-body. 35

B is the pad-cover, made from some proper material, of which compounds of vulcanized rubber are preferred. I make the pad B sufficiently thick and rigid to enable it to maintain its place and position on the step; and I provide it with an open pocket constituted by a continuous underturned margin, *d*, on its underside, into which pocket the plate or tread composing the step is introduced and retained 40 by being confined within said pocket around all its edges, excepting only at that point where the leg *g* departs from it. This is clearly shown in Fig. 2.

Having described my invention, I claim as 50 new—

A cover pad for carriage-steps, composed of a plate or pad, B, provided on its under side with a continuous under-turned margin, *d*, constituting a pocket adapted to receive and inclose all the edge of the step-plate, except at 55 the point where the step-arm is joined to said plate, whereby said pad will be retained in place without other fastenings, substantially as set forth.

JOHN T. DICKEY.
